CLAIM

The ornamental design for a flexible video endoscope, as shown and described.

DESCRIPTION

FIG. 1 is a front perspective view of a flexible video endoscope according to the present invention.

FIG. 2 is another front perspective view of the flexible video endoscope of FIG. 1.

FIG. 3 is a front view of the flexible video endoscope of FIG. 1.

FIG. 4 is a left side view of the flexible video endoscope of FIG. 1.

FIG. 5 is a right side view of the flexible video endoscope of FIG. 1.

FIG. 6 is a top view of the flexible video endoscope of FIG. 1; and,

FIG. 7 is a bottom view of the flexible video endoscope of FIG. 1.

The dash-dash broken lines in FIG. 3 depict portions of the flexible video endoscope that form no part of the claimed design. The remaining dash-dash and dot-dash broken lines depict environmental subject matter that forms no part of the claimed design.

1 Claim, 7 Drawing Sheets
